A. OSBORNE.

FACING FOR FIRE PLACES.

No. 14,384.

Patented Oct. 30, 1883.

UNITED STATES PATENT OFFICE.

ARTHUR OSBORNE, OF HYDE PARK, MASSACHUSETTS, ASSIGNOR TO
WILLIAM H. JACKSON, OF NEW YORK, N. Y.

DESIGN FOR A FACING FOR A FIRE-PLACE.

SPECIFICATION forming part of Design No. 14,384, dated October 30, 1883.

Application filed August 3, 1883. Term of patent 7 years.

To all whom it may concern:

Be it known that I, ARTHUR OSBORNE, a citizen of Great Britain, residing at Hyde Park, county of Norfolk, Massachusetts, have 5 invented and produced a new and original Design for the Facing or Frieze of Fire-place Casings, of which the following is a specification, reference being had to the accompanying drawing, forming part thereof.

to The drawing represents a front elevation of my newly-designed facing or frieze.

Fronts or casings for fire-places and grates are generally distinguished, when viewed in elevation, by separate raised or depressed figures of natural or ideal objects, leaving a large 15 part of the surface plane.

The leading and characteristic feature of this new design for the frieze of the entablature of the casing, when viewed in elevation, 20 consists in figures in relief representing laurel leaves and berries in clusters, arranged as on a vine, with uniting irregular crooked stems substantially covering the panel of the frieze within its marginal border.

The marginal border A of the panel of foliage and berries consists of a dentilated center transverse to a three-beaded molding upon each side thereof, and a simple flower or rosette of eight leaves, with a small center button at the ends or corners, as shown. The 30 panel of the frieze is inclosed by the border, excepting a portion at the bottom near each end, where the figure of laurel foliage extends, and covers the surface to the lower edge, so that it may join similar foliage that may be 35 used on pilasters or jamb-facings upon which the frieze may be mounted.

I claim as my invention—

The design for a facing or entablature for a fire-place herein shown and described, the 40 same consisting of the representation of laurel leaves and berries, with indented beaded rosette border.

ARTHUR OSBORNE.
